A. NAPOLITANO

LEATHER MAT

Filed Feb. 6, 1924

INVENTOR.

Aristide Napolitano

Miller, Henry Boykin
ATTORNEY.

UNITED STATES PATENT OFFICE.

ARISTIDE NAPOLITANO, OF SAN FRANCISCO, CALIFORNIA, ASSIGNOR TO LEATHER MAT MANUFACTURING COMPANY, OF SAN FRANCISCO, CALIFORNIA, A CORPORATION OF CALIFORNIA.

LEATHER MAT.

Application filed February 6, 1924. Serial No. 691,020.

My invention has for its object improvements in the construction of leather mats whereby I attain greater efficiency both in construction and operation.

One of the objects of my invention is to provide a mat of the character described whereby the edges of the mat are provided with a reinforced sloping surface to prevent the shoes of pedestrians from stumbling over the mat. Other objects are reinforcements to securely hold the leather link portions in proper alignment. Another object is means for fastening a mat of the character described to the floor. A further object is the providing of elongated links about boundary portions or edges of the mat to avoid the side openings within which dust and débris has heretofore collected in mats of this class.

Other objects will appear from the drawings and specifications which follow.

Fig. 1 is a sectional view of a portion of a leather mat to which my invention has been applied, and is taken on the line I—I of Fig. 2.

Fig. 2 is a plan view of a mat to which my invention has been applied.

Fig. 3 is a side view of the mat of Fig. 2, showing the elongated links on one edge.

Fig. 4 is a cross section of the pintle fastening means of Fig. 2 on the line 4—4 thereof.

Fig. 5 is a cross section through one of the sloping ends of Fig. 2 on the line 5—5 thereof.

Throughout the figures similar numerals refer to identical parts.

The numeral 1 indicates the standard form of link of a plurality of which the greater portion of the mat is constructed. Each of these links is built up of a number of similar pieces of leather turned on edge and bound together by pintle or cross bars as 2, 4, 14. The other ends of adjacent links are turned right and left and interlaced with other similar links and pintle bars as shown. The cross bar 2 is bent over on one end as shown at 3 and back parallel with 2 at 4 forming a U shaped member whereby the links threaded thereon and as above described are firmly held in respective hinge relation.

End plates, as 5, 6, reinforce the terminal links, and the bars 2 and 4 are then bent

over at their ends as shown at 7, 8 and held in fixed relation by pressing therearound a thimble or retainer, 9.

At suitable locations within the built up mat, I introduce metallic angle plates, two of which are shown at 9 and 10 and through which holding screws 11 enable the mat to be fixed to the floor. The said angle plates have upstanding edge portions 12 and 13 respectively through which one of the cross bars as 14 Fig. 2 is passed. The mat is thus fixed in hinge relation to the said fastening plates.

The edges of the mat, in the direction of pedestrian travel, I form with special long and short sloping links 15, 16, respectively, whereby the shoe of a pedestrian treads upon the sloping surface without stumbling. These long and short sloping links are alternately spaced and the long links are hinged with the standard links as 1. The long links 15 being placed at each end of the sloping edge and the U bar 14, 17, 18 being passed through the two ends of the links and fastened on the end by the thimble 19 in the same manner as the U bar 2, 3, 4. This leaves the shorter end links 16—16 pivoted to the bar 18 on one end, and through their other ends I pass the idler bar 20 preferably terminating just within the end plates 21, 22 of the outer long links 15.

These terminal plates 21, 22, I prefer to make of metal substituting a metallic plate for the outer thickness of leather.

It will now be seen that the bar 20 in combination with the bar 18 maintains at all times the proper alignment of all of the edge links 15, 16, thus giving a smooth and rigid sloping surface for the entire width of the mat, hinged to the body of the mat by the bar and forming in effect an integral hinged apron. It will be noted that between the links 1—1 that are in alignment, there is left an open space, and if links of the same length be employed on the edges of the mat as heretofore, there would be corresponding spaces between them in which dirt and débris would collect and be difficult to remove by the ordinary floor brushes. These end links I therefore make longer as shown at 23—23 so that their ends practically roll together when the mat is rolled, without any material space therebetween. In this way the edge of the mat has a con-

tinuous appearance and is readily cleaned by running a brush along the edge in a linear direction. These end links 23-23 are pivoted on the pintle cross bars as 2-4 and on the same centers as the links 1-1.

I claim:

1. In an articulated leather link mat comprising longitudinally spaced rows of links connected transversely by pintle bars, fastening lugs carried by the bars and having each a portion lying within the spaces be-

tween the ends of the links for securing the mat to the floor.

2. In an articulated leather link mat comprising longitudinally spaced rows of links connected transversely by pintle bars, fastening lugs pivoted on the bars having each a plate portion lying within the spaces between the ends of the links substantially flush with the lower side of the mat for securing the mat to the floor.

ARISTIDE NAPOLITANO.
